UNITED STATES PATENT OFFICE

2,507,658

LABEL CODER ATTACHMENT

Francis C. Worth, Brooklyn, N. Y.

Application January 19, 1948, Serial No. 2,972

5 Claims. (Cl. 216—2)

1

This invention relates to a sheet material printing apparatus employed particularly for printing code numbers or letters on labels.

An object of this invention is to print or stamp labels with code numbers or letters in a machine, which machine includes apparatus for performing the function of maintaining a stack of labels at a predetermined height, lifting the top label of the stack and transporting it to a receptacle, thence pressing the label on the said receptacle.

Another purpose of this invention is similar to the aforementioned object. However, it is to utilize the label printing or stamping operation in existing machines also including the step of applying glue or the like to the label before application to a receptacle.

Another object of this invention is to print a label with code letters or numbers prior to its application to a receptacle, which label printing is performed by the addition of type to a conventional feeler arm of an existing machine, which arm is also utilized for regulating the lifting mechanism for maintaining the top of the stack of labels at a predetermined elevation.

Another purpose of this invention is to maintain a supply of ink or the like on the apparatus for lifting the top label of the stack and to apply a small portion of this ink supply to the type which is detachably positioned on the feeler arm.

Another object of this invention is to apply an attachment to an existing label applying machine whereby label printing may be done automatically with the label application operation, thereby obviating the necessity of coding the labels prior to placing them in the conventional machine or subsequent to the application on receptacles.

Ancillary objects and features of novelty such as simplicity in structure will become apparent in following the description of the preferred form of the invention, illustrated in the accompanying drawings, wherein:

Figure 1 is a sectional view of one form of the invention, showing the improved portion in elevation;

Figure 2 is a sectional view, similar to that shown in Figure 1, however, a different portion of the cycle of operation is illustrated;

Figure 3 is a plan view of the invention shown in Figures 1 and 2;

Figure 4 is an enlarged fragmentary sectional view illustrating the drive means for the drive shaft to be subsequently described;

Figure 5 is an enlarged fragmentary elevational view illustrating the suction plate for lifting labels and showing the ink supply and applicator;

2

Figure 6 is a plan view of the ramps and ink applicator utilized in association with the invention and forming a portion thereof, and;

Figure 7 is a bottom view of the feeler arm showing the type fixed thereto.

This invention relates to a device, which is capable of stamping or printing the top label of a stack of labels. Conventional machines for fixing labels to receptacles, vials, cans, bottles and the like simply perform this single function. However, it is often necessary to stamp code numbers on previously printed individual labels with the date and other pertinent indicia, which operation generally requires a separate machine. It is within the purview of the present invention to apply the label printing apparatus to conventional, existing machines, whereby an entire physical step in the operation of receptacle preparation is obviated. Of course, a prime field of utility of the present invention is in conjunction with receptacles used for pharmaceutical products. However, the device may be used in association with any type of material bearing receptacle.

There has been great difficulty in attempting to print or stamp the top label of a stack of labels due to the inherent resiliency of this stack. In the present invention this resiliency is utilized to advantage rendering the stamping operation possible. The conventional apparatus for fixing labels to receptacles is extremely complex and therefore, only those elements which are required to illustrate an operative device are shown in the drawings, the extremely complicated adjustments, relays, electrical wiring, timing devices, etc. have been omitted in order that the basic principles of the invention may not be obscured.

Where an expensive, very large casting is supplied as a foundation for the operative elements of the conventional machine, the applicant has illustrated a support generally indicated at 10 and composed of a plurality of angle iron members. These angle iron members are placed wherever, it is deemed necessary to form an operative machine.

The general operation and structure of the conventional machine is as follows:

The support 10 serves as a journaling member for a shaft 12 which is received in suitable, conventional bearings 14. A plurality of cams 16 and 18 respectively are secured to the said shaft 12 and the function of the said cams will be described hereinafter.

Means for oscillating the said shaft is provided. This means may be seen best in Figure 4

wherein a gear 20 is disclosed as being rigidly secured to the said shaft 12 and a rack gear 22 is shown communicating therewith. A guide 24 may be supplied on a selected frame member 26 for the purpose of restricting the rack 22 to reciprocal travel.

A suitable source of power is supplied (unshown) and a conventional drive such as the pulley 28 may be journalled on a shaft 30 which is in turn positioned in suitable bearings 32. These bearings are rigidly secured to a support member 34. An eccentric 36 is secured to the said shaft 30 which is driven by the said pulley 28 and a cam follower 38 is supplied on the rack 22, being engageable with the periphery of the eccentric or cam 36. Through this construction the shaft 12 is actuated in ever reversing directions.

An arm 40 is secured to the shaft 12 and has bends therein. This arm is received in a suitable slot within a link 42 which is journalled in a guide 44 positioned in a cross member 46 of the support 18. Upon oscillatory movement of the shaft 12, the arm 40 is raised and lowered, thereby lifting the link 42 selectively up and down. A receptacle engaging member 47 is supplied at the terminal portion of the link 42 and is adapted to press a label on the surface of a receptacle 48 which is received on a support 50. As is conventional, the receptacle 48 is one of many which is positioned on an endless conveyor.

A rail 52 extending longitudinally of the said support 18 is provided with a slide or shoe 54 which is connected therewith by a tongue and groove, dovetail or the like construction. A dovetail slot 56 is formed in the shoe 54, for receiving a complementally configured plate 58.

Means for periodically sliding the shoe 54 longitudinally of the rail 52 is provided. This consists of the cam or eccentric 18 which is secured to the shaft 12. As the shaft oscillates, it carries the eccentric 16, which, in turn, carries a push rod 60, the push rod 62 being pivoted thereto. The terminal portion of the push rod is fork-shaped and engages a pin 62, which is positioned between the tines of the fork or fork-shaped portion. A pin 64 extends through the said push rod 60 and is journalled in the aforementioned shoe 54. Through the medium of this pin 64, the shoe is urged selectively down and up the rail 52. During this movement, the plate 58 is also raised and lowered due to the arcuate movement of the pin 62 about the said pin 64.

A suction head 66 is secured to the plate 58. An upper plate 68 is interposed between the terminal of the said dovetail plate 58 and the suction head 66 and may have a suction hose 70 secured thereto. Of course, a suitable pump is utilized in association with the suction hose 70 as a vacuum producing means. It is readily apparent now that suction means for lifting the top label of a stack of labels 72 is provided and has a motion such that the top label may be removed from the stack to the receptacle 48.

Means for maintaining the stack of labels 72 and for supporting the stack is provided. The cam 16 is utilized as a source of power for this movement. A bell crank 74 is pivotally journalled through the medium of a pin 76 extending through and journalled in the said rail 52. One end of the bell crank 74 contains a cam follower 77 engaging the said cam 16 while the other end is bifurcated, the bifurcations being indicated at 78.

A feeler arm 80, right angular in configuration,

is journalled in a slide 84 which is secured to the rail 52. A pin 86 is secured to the said feeler arm adjacent one end thereof and is engageable between the bifurcations 78. Upon oscillatory movement of the shaft 12, the bell crank 74 is pivoted about the pin 76, thereby raising and lowering the feeler arm 80 a predetermined amount.

A swinging arm 87 is pivoted by any suitable means to the support 10 and has a dog 88 pivoted at one end thereof. This dog engages the teeth of a ratchet gear 90 journalled in the support 10. A gear 92 is rigidly secured to the said ratchet gear 90 and is engageable with the teeth of a rack gear 94. The rack gear 94 is slidably positioned in a guide 96 which is secured to the support 10. A platform 98 is positioned at one terminal of the rack gear 94 and it is thereupon that the stack of labels 72 seats.

A bracket 100 is secured to the bell crank 74 and has an adjustment screw 102 positioned therein. This adjustment screw engages the swinging arm 87 upon movement of the bell crank 74. The feeler arm 80 reciprocates due to the movement of and influenced by the movement of the bell crank 74. The top label of the stack of labels restricts the travel or limits the travel of the movement of the feeler arm. When this stack of labels decreases a predetermined amount, the swinging arm 87 is engaged by the adjustable screw 102, thereby lifting the stack a distance equal to an amount commensurate with the size of one tooth of the said ratchet gear 90.

Referring now to Figures 5, 6 and 7, it will be noted that the feeler arm is provided with a head 104 which is detachably secured at the end thereof by means of a suitable screw 106 or the like. A row of print 108 is provided in the head 104 and this row of print engages the top label of the stack of labels 72 for the purpose of regulating the height of the labels. Also, this row of print actually prints or stamps the top label.

The plate 68 is provided with a pair of ramps 110 and 112 respectively whereon the edges of the said head 104 slide during a portion of a single cycle of operation of the device. Juxtaposed relative to the said pair of ramps is a roller 114 which may be positioned over any pad, well or the like. A small amount of ink is picked up by the roller 114 upon rotation thereof, which small portion is transferred to the line of type in the head 104. The roller 114 is provided with rollers 116 and 118 respectively which flank the roller 114 and all of the rollers are journalled on a suitable shaft 120 which is received in conventional brackets 122 on the plate 22. It is noted at this point that the ink supply is received on the vacuum or suction producing plate elements in order that the type may be supplied with ink while the suction producing means is raising the top layer of the stack of labels 72. Also, the supply of ink is removed when the feeler arm is performing its operation and also when the feeler arm is being utilized to print the top layer of the stack of labels.

In order to bias the arm 87 for effective operation of the dog or pawl 88, a tension spring 130 is secured thereto and the shaft 30. This spring 130 constantly urges the arm 87 in the proper direction.

In certain types of machines the label is supplied with mucilage or glue before being fixed to the receptacle 48. This operation may be performed by simply supplying a quantity of glue

in an applicator in the path of travel of the label retaining and transporting head 66.

It is apparent that variations may be made without departing from the spirit of the invention.

Having described the invention, what is claimed as new is:

1. A label printing machine including a support, a shaft in said support, a rack slidably secured to said support for supporting a stack consisting of a plurality of labels, means for periodically raising said rack associated with said shaft and said rack, said raising means including a feeler arm slidably secured to said support, a cam on said shaft and a crank pivoted to said support engaging said cam and secured to said feeler arm for actuation thereof, a suction head for lifting the top label from the stack and depositing it on a receptacle, means on said feeler arm for printing on the top label of the stack, means for periodically applying ink to the printing means including a shoe slidably mounted on the support and having said suction head secured thereto, a ramp secured to said shoe, and an ink applicator mounted on said plate adjacent said ramp.

2. An apparatus for printing code numbers and letters on labels and attaching them to receptacles comprising a support, a shaft having cams journaled in said support, a rack for supporting a stack of labels, means for raising said rack including a feeler arm slidably mounted in said support, a crank engaging one of said cams and rocked thereby, means connecting said crank and said feeler arm for reciprocating said feeler arm, means for raising said rack responsive to and rendered operative upon a predetermined travel of said feeler arm, means for periodically lifting a label and depositing the label on a receptacle, said lifting means having means associated therewith slidably mounting said lifting means on said support, means including type mounted on said feeler arm for printing the top label on the rack, means for applying ink to said coding means including an ink applying member secured to said label lifting means, and said ink applying member having a ramp in advance thereof to guide said feeler arm and said type on said member.

3. In an apparatus for printing code markings on a stack of labels and for moving the printed top label of the stack for deposit on a receptacle, which apparatus includes means for periodically lifting the stack of labels in response to depletion

of the stack, an attachment comprising a feeler arm with means for reciprocating the feeler arm, a suction head to lift the top label of the stack of labels and to deposit it on the receptacle, said feeler arm having a printing head, and means carried by the suction head for applying ink to the printing head.

4. In an apparatus for printing code markings on a stack of labels and for moving the printed top label of the stack for deposit on a receptacle, which apparatus includes means for periodically lifting the stack of labels in response to depletion of the stack, an attachment comprising a feeler arm with means for reciprocating the feeler arm, a suction head to lift the top label of the stack of labels and to deposit it on the receptacle, said feeler arm having a printing head, and means carried by the suction head for applying ink to the printing head including an ink applicator member secured to said suction head, and a ramp secured to said suction head to guide the printing head on the ink applicator member.

5. In a label printing apparatus which includes a support with a crank mounted on said support and a feeler arm mounted for reciprocatory movement on the support, means operatively connecting said crank and said feeler arm so that the crank operates said feeler arm in the reciprocatory movement, means for supporting a stack of labels in the travel of said feeler arm together with means for periodically raising the foregoing means to maintain the top of the stack of labels raised, a shoe displaceably mounted on said support and movable from a position over said stack of labels to a position over a device for supporting a receptacle, a suction head secured to said feeler arm for picking up the top label of the stack and depositing it on the receptacle, and said feeler arm having type carried thereby and means for applying ink to the type carried by said suction head and engageable with said type.
